UNITED STATES PATENT OFFICE.

ALBERT L. TAUTE, OF MORA, MINNESOTA.

RADIATOR.

1,420,590.

Specification of Letters Patent. Patented June 20, 1922.

Application filed March 28, 1918. Serial No. 225,233.

To all whom it may concern:

Be it known that I, ALBERT L. TAUTE, a citizen of the United States, residing at Mora, in the county of Kanabec and State of Minnesota, have invented a new and useful Radiator, of which the following is a specification.

The device forming the subject matter of this application is a radiator adapted for use 10 on automobiles, and the invention aims to provide novel means whereby the effective surface of the radiator may be decreased or increased, depending on weather conditions and the like.

15 It is within the province of the disclosure to improve generally and to enhance the utility of devices of that type to which the present invention appertains.

With the above and other objects in view, 20 which will appear as the description proceeds, the invention resides in the combination and arrangement of parts and in details of construction hereinafter described and claimed, it being understood that, within 25 in the scope of what is claimed, changes in the precise embodiment of the invention shown can be made without departing from the spirit of the invention.

In the accompanying drawings:—

30 Figure 1 shows a front elevation of a radiator constructed in accordance with the invention, parts being broken away; Figure 2 is a section on the line 2—2 of Figure 1; and Figure 3 is a section on the line 3—3 35 of Figure 1.

In carrying out the invention there is provided a radiator 1, having the usual filling nipple 2. The radiator comprises a top compartment 3, a bottom compartment 4 and 40 side conduits 5 connecting the compartments 3 and 4. Disposed within the space defined

by the compartment 3, the compartment 4 and the conduits 5 is an auxiliary structure including a top header 6, a bottom header 7 and flues 8 connecting the headers. Casings 45 9 are located at the ends of the headers 6 and 7 and in the casings, valves 10 are journaled, valves 10 being adapted to be manipulated by means of exposed finger pieces 11.

It will be obvious that when the valves 10 are opened, the water will circulate not only through the compartments 3 and 4 and the conduits 5 but, as well, through the headers 6 and 7 and through the flues 8. By closing the valves 10, the flues 8 and the headers 6 55 and 7 may be cut off, thereby decreasing the radiating surface.

Having thus described the invention, what is claimed is:—

A radiator comprising a main member 60 having a central opening and embodying a top compartment, a bottom compartment, and side conduits communicating at their ends with the compartments and having inner walls; an auxiliary member fitting within the central opening of the main member and including a top header, a bottom header and flues connecting the headers; valve casings mounted in the ends of the headers and in the inner walls of the conduits and constituting means for connecting the auxiliary member with the main member; and valves in the casings, the valves controlling communication between the headers and the conduits. 70 75

In testimony that I claim the foregoing as my own, I have hereto affixed my signature in the presence of two witnesses.

ALBERT L. TAUTE.
